UNITED STATES PATENT OFFICE.

LEO EDELMANN, OF CHICAGO, ILLINOIS, ASSIGNOR TO E. EDELMANN & CO., OF CHICAGO, ILLINOIS, A CORPORATION OF ILLINOIS.

DESIGN FOR A BATTERY TESTER OR THE LIKE.

Application filed October 5, 1928. Serial No. 28,377. Term of patent 14 years.

To all whom it may concern:

Be it known that I, LEO EDELMANN, a citizen of the United States, residing at Chicago, in the county of Cook and State of Illinois, have invented a new, original, and ornamental Design for a Battery Tester or the like, of which the following is a specification, reference being had to the accompanying drawing, forming part thereof.

Figure 1 is a view in side elevation with a syringe barrel and bulb shown in dotted lines.

Fig. 2 is an enlarged side elevation.

Fig. 3 is a transverse section on line 3—3 of Fig. 2.

Fig. 4 is a fragmentary longitudinal sectional view on line 4—4 of Fig. 3.

Fig. 5 is a view in end elevation.

I claim:

The ornamental design for a battery tester or the like, as shown.

LEO EDELMANN.
